UNITED STATES PATENT OFFICE.

ELVAH C. SMITH AND JAMES O. SMITH, OF NEWTON, IOWA.

MILL FOR CUTTING GRAIN.

SPECIFICATION forming part of Letters Patent No. 594,972, dated December 7, 1897.

Application filed April 10, 1897. Serial No. 631,514. (No model.)

To all whom it may concern:

Be it known that we, ELVAH C. SMITH and JAMES O. SMITH, citizens of the United States, residing at Newton, in the county of Jasper and State of Iowa, have invented a new and useful Mill for Cutting Grains of Wheat, Corn, Oats, &c., of which the following is a specification.

Our object is to provide a simple, strong, durable, and efficient portable mill for cutting grains of wheat, oats, corn, &c., into particles adapted for food for man and beast.

Our invention consists in the construction, arrangement, and combination of one or more cylinders carrying cutters, and means for simultaneously adjusting the cutters relative to a stationary cutter with a suitable frame or case, as hereinafter set forth, pointed out in our claims, and illustrated in the accompanying drawings, in which—

Figure 1 shows an outside view of a portion of one of our cylinders. Fig. 2 is a face view of the finished end of Fig. 1. Fig. 3 is a longitudinal sectional view of Fig. 1. Fig. 4 is a transverse sectional view on the line xx of Fig. 1. Fig. 5 is a vertical sectional view of our mill, showing two cylinders arranged and combined with a hopper to be operated simultaneously as required to facilitate the speedy cutting of grain fed to the cutters from the intervening single hopper. Fig. 6 is an outside face view of the mill. Fig. 7 is a perspective view of a piece of a frame adapted for adjustably fastening detachable cutters thereto and also fastening the ends of the frame adjustably to the parallel sides of the case. Fig. 8 is an end view of the mill, showing the two cylinders connected with driving mechanism. Figs. 9 and 10 show a modified form in which the cylinders are closer together and a single cutter-support adjustably connected therewith. Fig. 11 is a detail view showing the manner of combining and adjusting a single cutter-support with the two cylinders. Figs. 12 and 13 show a mill having a single cylinder mounted upon a frame.

The letter A designates a metal cylinder that may vary in length and diameter as desired.

B is a shaft fixed in the cylinder and provided with journals on its ends that extend

through bearing L, formed on or fixed to the parallel sides of the case, as shown in Fig. 8. Sections of the end portions of the shaft are 55 screw-threaded for the application and operation of devices for adjusting and locking cutters fitted in slots formed in the cylinders. Seats C for removable and adjustable cutters in the form of straight slots or kerfs are 60 cut inward from the periphery to extend straight from end to end of the cylinder and tangentially relative to the curved surface, as clearly shown in Fig. 4. Straight cutters d are fitted in said seats C and provided with 65 integral tapering extensions d' at their ends that project outward from the ends of the cylinder A to be engaged by a collar F, that is fitted to the screw-threaded portion of the shaft B. The outside surface of this collar 70 is screw-threaded and its inner edge beveled to fit against the under sides of the beveled extensions d' of the cutters d.

H is a ring provided with an annular lateral extension H² and fixed to the end of the cylinder A by means of tap-bolts and in concentric position with the shaft B.

F² is a collar that has an internal screw fitted to the exterior of the collar F and its inner edge beveled to engage the outer tapered 80 edges of the extensions d' of the cutters d.

F³ represents a metal guard fixed to the ring H to prevent grain from falling outside of the ring into the annular vacant space that surrounds the flange H².

J is a nut fitted on the screw-threaded portion of the shaft B to lock the adjustable parts in fixed positions.

Each end of each cylinder A is formed in the same manner and provided with the same 90 kind of devices for adjusting the cutters and locking them in fixed positions.

The frame or case adapted to support the cylinders is composed of two parallel sides K (preferably metal) and two end pieces K², 95 rigidly united by casting them together in molds or in any suitable way. Bearings L for the shaft B are formed on or fixed to the sides K, as shown in Fig. 8.

L² is an inclined plane fixed in the case and 100 extends out through an opening in one of the ends thereof.

M are cutter-supports adjustably connected with the sides K to support cutters M², bolted

- thereto. These supports are cast in molds and have inclined flanges N at their top edges and right-angled ends N^2 , provided with curved slots P , through which bolts P^2 are extended through perforations in the parallel sides K to receive nuts as required to clamp the cutter-supports fast thereto and thereby adjustably connect the cutter M^2 with the machine to coöperate with the cutters d , carried by the cylinders A . Annular flanges K^3 , projecting outward around corresponding openings in the parallel sides K , admit the ends of a wooden cutter-support M^3 in such a manner that said support, having cutters M^2 adjustably and detachably fastened thereto, can be readily adjusted by means of set-screws as required to raise and lower the cutters M^2 relative to the cutters d , carried by the cylinders A .
- A^2 is a cover hinged to one of the ends K^2 of the case and has a hopper R at its center and a double-inclined fixed bottom R^2 , adapted to direct grain to the parallel cylinders A . Cut-off slides S are fitted in slots in the hopper to direct and control the flow of grain from the hopper.

In the practical operation of our mill the plurality of cutters d in a cylinder can be readily and simultaneously adjusted as required to cut grains into fine or coarse food. The closer the sharp edges of the cutters d come to the sharp edge of the fixed cutter M^2 as the cylinder rotates toward the said fixed cutter the finer will be the product of the mill. To move the cutters d outward, the locking-collars F^2 must be moved outward, and the collars F then moved inward relative to the ends of the cylinder A , and the locking-collars F^2 then also moved inward to again simultaneously lock all the cutters d by the contact of the beveled inner edges of the locking-collars with the outside tapering edges of the integral projections d' at the ends of the cutters d .

When the cutters d and M^2 are adjusted relative to each other as desired, grain will be fed to the cylinders A through the hopper R , and the flow or quantity regulated by means of the slides S , and the cutters rotated toward each other by means of power applied to a belt-wheel B^2 and the gear-wheels on the ends of the parallel shafts of the two cylinders A .

We claim as our invention—

1. In a mill for cutting grain, a cylinder having straight slots extending from end to end longitudinally and tangentially to a circle within that of the cylinder, straight cutters fitted in said slots and having tapering extensions at their ends, a shaft extended from the ends of the cylinder and portions thereof screw-threaded, collars having external screws and beveled at the edge on their inner ends to engage the inner edges of the tapering extensions of the said cutters fitted to the screw-threaded portions of the shaft, locking-collars fitted on the collars on the

shaft and beveled at their inner ends to engage the outside edges of the tapering extensions of the adjustable cutters, and means for fastening the movable collars in fixed positions relative to the shaft and cylinder, arranged and combined to operate in the manner set forth for the purposes stated. 70

2. In a mill for cutting grain, a cylinder having straight slots extending from end to end longitudinally and tangentially to a circle within that of the cylinder, straight cutters fitted in said slots and having tapering extensions at their ends, a shaft extended from the ends of the cylinder and portions thereof screw-threaded, collars having external screws and beveled at their outside inner edges to engage the inner edges of the tapering extensions of the said cutters fitted to the screw-threaded portions of the shaft, locking-collars fitted on the collars on the shaft and beveled at their inner ends to engage the outside edges of the tapering extensions of the adjustable cutter, and means for fastening the movable collars in fixed positions relative to the shaft and cylinder, rings fixed to the ends of the cylinder and provided with annular flanges extending at right angles to cover the concentric collars on the shaft, arranged and combined to operate in the manner set forth for the purposes stated. 85

3. In a mill for cutting grain, a cutter-support consisting of a metal frame having a flat straight central part and an inclined flange at its top edge, right-angled end portions provided with curved slots and straight cutters adjustably fixed to the central portion, in combination with the parallel sides of a frame or case, and a cylinder carrying adjustable cutters mounted upon said frame or case, arranged and combined to operate in the manner set forth, for the purposes stated. 100

4. A mill for cutting grain, comprising a frame or case having an inclined bottom, a hinged top or cover, a hopper fixed to the cover, a bottom in the hopper inclined in reverse ways from its center, two cylinders mounted in parallel position on opposite sides of the hopper, adjustable cutters having internal tapering extensions at their ends fitted in slots extended tangentially to the circles within those of the cylinders, collars having beveled edges to engage said extensions for adjusting and locking said cutters in the cylinders, cutter-supports, having straight cutters adjustably fixed thereto, adjustably connected with the parallel sides of the frame or case to extend parallel with the cutters carried by the cylinders, and means for rotating the cylinders toward each other, all arranged and combined to operate in the manner set forth, for the purposes stated. 115
